UNITED STATES PATENT OFFICE

ALLEN B. DOWELL, OF ST. LOUIS, MISSOURI

HIGHWAY GUARD FENCE

Application filed March 24, 1930. Serial No. 438,306.

This invention relates to new and useful improvements in the construction of road guards and fences.

Heretofore road guards of the type to which this invention relates have been made generally of wood construction and consisted of wooden uprights driven into the ground at regular intervals and having one or more horizontally disposed rails extending between each pair of adjacent uprights and bolted or nailed thereto. Both the posts and the rails had to be made of heavy lumber and had to be dressed and painted. As a large number of such guards is used the expenses of construction and maintenance is very great. The uprights and rails have to be painted regularly which is quite an item in the cost of maintenance, and the bolts or nails used to secure the rails to the uprights will rust in the course of time and have to be replaced and will also cause decay of the rails.

Furthermore, where such lumber is treated with a preservative, it cannot be painted satisfactorily and is unsightly and not readily visible in the dark.

The objects of the present invention are to provide uprights of reinforced concrete adapted to be anchored in the ground and having their exposed portions provided with suitable recesses into which are adapted to be received and anchored therein the ends of the horizontally disposed rails. The recesses are arranged in pairs, each pair being arranged on the same horizontal plane and preferably arranged in communication with each other whereby the respective ends of the rails can be interengaged or interlocked with each other within said recesses.

Other objects of the invention are to provide an improved road guard and fence construction comprising uprights of reinforced concrete adapted to be embedded in the ground and having the exposed portion provided with one or more pairs of recesses, each

pair of recesses being arranged on the same horizontal plane and in different faces of the upright, and to provide rails having reducing ends fitting into said recesses and having said reduced ends provided with suitable longitudinally arranged projections whereby the adjoining ends of each pair of rails can be interlocked, thereby holding said rails against disengagement from said upright.

Still other objects of the invention are to provide uprights of reinforced concrete having their upper portions provided with two recesses disposed in the different sides of said upright and arranged on the same horizontal plane with each other, and to provide rails of reinforced concrete, each of said rails having formed at each end a reduced extension which fits loosely within the recess of the upright, while the vertical wall of each end is in abutting contact with the corresponding recessed side wall of said upright, and to provide means for anchoring said reduced extensions within said recesses.

With these and other objects in view, my invention consists in certain novel features of construction and arrangement of parts, hereinafter more fully described and claimed, and illustrated in the accompanying drawings, in which—

Figure 1 is a fragmental front elevational view of a road guard of my improved construction.

Figure 2 is an enlarged front elevational view of one of the uprights, the upper portion thereof being broken away to show the ends of the rails seated in the recesses thereof.

Figure 3 is a vertical cross section taken transversely through the rails and showing one of the uprights in elevation.

Figure 4 is an enlarged horizontal cross section taken through the upright and showing the ends of the rails in elevation.

Figure 5 is an enlarged perspective detail

view showing one end of the rail of my improved construction.

Figure 6 is a similar view showing the other end of said rail.

5 Figure 7 is a horizontal cross section through a corner construction showing the arrangement of recesses and rails.

Referring by numerals to the accompanying drawings, 10 indicates a plurality of uprights formed of reinforced concrete and 11 indicates rails disposed horizontally between each pair of uprights and having their ends seated therein. Each upright 10 has preferably parallel vertically disposed sides 12 and 15 obliquely disposed front and rear sides 14.

Each upright is reinforced by a pair of substantially U-shaped steel bars 15 which are spaced from each other and are embedded in the upright with the ends terminating in the lower end of the upright and with the curved portion of each reinforcing bar arranged in the upper end of the upright as shown in Figure 3. Preferably the upper end of the upright is curved to correspond with the disposition of the curved portions of bars 15. The lower portion of each upright is adapted to be anchored in the ground as shown at 16 and in locating the uprights in position the hole is preferably 20 dug larger than the cross sectional area of each upright so that concrete can be poured in the hole and around said upright, thereby providing a bed of concrete 17 which securely anchors the upright in position and increases the weight of the lower end thereof so as to enable it to withstand more successfully impacts delivered thereagainst.

40 Each side wall 12 of the upright is provided with one or more recesses 18 and the recesses of one side wall are arranged on the same horizontal planes with the recesses on the opposite side so that the bottom walls 18^a of each pair of corresponding recesses is substantially on the same horizontal plane.

45 The recesses of one side of each upright are of greater height than the recesses of the other side, thereby providing clearance openings 18^b.

The rails or horizontal bars 11 extend between each pair of uprights 10 and each rail is provided with reduced ends 19, thereby forming shoulders 11^a. The reduced ends 19 are inserted into corresponding recesses 18 of the spaced uprights 10. The cross sectional area of each end 19 is considerably less than the cross sectional area of the recess 18 so that said ends can be readily inserted thereto. When the reduced ends 19 are in position, the space is filled or grouted 55 with cement which seals the recesses and secures the ends 19 in position.

Each rail 11 is reinforced by longitudinally disposed rods 20 arranged near each corner and by a rod 21 disposed centrally of 60 the rail. The ends of rod 21 extend beyond

the reduced ends 19 and one end of said rod is formed to provide a horizontally disposed eye 22 while the other end of the rod is shaped to provide a downwardly presented hook 24. The length of each reduced end 19 is less than the depth of recess 18 and the distance between shoulder portion 11^a and the axis of the eye 22 is equal to the distance between the shoulder portion 11^a and the axis of hook 24. Thus when the reduced ends 19 of the adjoining rails 11 are inserted in the respective recesses, hook 24 of one rail engages the eye 22 of the other rail, thereby tying said rails together. This arrangement unifies the structure so that the strain imparted to one of the rails is transmitted not only to the corresponding uprights but also to the adjacent rails and through the latter to the other uprights. In this manner a strong construction is provided which will successfully withstand any impact or blows to which the roadguard may be subjected. In the assemblage of the rails, the hooks 24 are arranged to occupy recesses 18^b which, being of greater height, have sufficient clearance to permit movement of the hook portions in vertical plane when bringing hooks 24 into engagement with eyes 22.

95 In the corner construction shown in Figure 7 one set of recesses 18 is arranged in the front wall 14^a at right angle to the recesses 18 of the side wall 12. Preferably this front wall 14^a is formed vertical the same as the side wall 12 instead of oblique as in the preceding form. The arrangement and method of securing the rails in position is substantially the same as in the form just described.

100 As shown in the drawings, rails 19 are used in pairs, the members of each pair being spaced vertically from each other. However, if so desired, only one rail may be used or three or more rails, if necessary. Where the construction is used for fences, the uprights 10 are of the required height and the rails 11 are spaced a suitable distance from each other to receive the fencing.

105 As both the uprights and the rails are formed of reinforced concrete, they can be economically manufactured and can be made of any desired strength and shape. When placed in position the metal portions, namely, eyes 22 and hooks 24, are located within recesses 18 and are sealed therein and there is no metal left exposed to the weather.

110 As my improved roadguard or fence is formed of concrete, it is of strong and durable construction and the cost and maintenance thereof is reduced to a minimum.

115 I claim:

1. A roadguard construction comprising in combination, a pair of uprights of reinforced concrete, each of which is provided in its two walls with aligned and communicating

5 recesses, and rails of reinforced concrete, each of which is provided at each end with a tenon, one tenon being provided with a metallic eye and the other end with a metallic hook whereby the ends of two adjoining rails can be locked with each other within the communicating recesses of said uprights.

10 2. A roadguard construction comprising in combination, a pair of uprights of reinforced concrete, each of which is provided in its opposite sides with recesses, each pair of recesses being arranged on the same horizontal plane and in communication with each other, and rails disposed horizontally between said uprights, the end of each rail being reduced in cross section and fitting loosely into one of the recesses, one reduced end of each rail being provided with an eye member embedded in said rail and extending therefrom and the other end of said rail being provided with a hook embedded in said rail and extending therefrom whereby the ends of two adjoining rails can be interlocked when occupying the aligned recesses, the recess being enlarged in 15 a vertical plane to permit upward displacement of said end of the rail preparatory to the seating of the hook into the eye of the rail engaging the other recess, the space between said reduced ends and said recesses being 20 filled with suitable material to close said spaces and seal said hook and eye portions.

25 3. In a construction of the class described, the combination of uprights of reinforced concrete provided on their opposite sides 30 with recesses arranged in pairs, the recesses of each pair being arranged on the opposite sides of the upright in a horizontal plane and communicating with each other, and rails of reinforced concrete having reduced ends 35 adapted to be seated in said recesses, each rail being provided with a centrally disposed metal rod, the ends of which project beyond said reduced ends and terminate in a hook and eye respectively whereby the ends of 40 the adjoining rails occupying the communicating recesses are locked together through the interengagement of said eye and hook portions, the recess receiving the hook end of 45 the rail being enlarged upwardly to permit upward displacement of the hook end of the rail preparatory to the engagement of said hook with the eye of the adjacent rail.

50 4. In a construction of the class described, the combination of uprights of reinforced concrete provided on their opposite sides 55 with recesses arranged in pairs, the recesses of each pair being arranged on the opposite sides of the upright in horizontal plane and communicating with each other, rails of reinforced concrete having reduced ends adapted 60 to be seated in said recesses, a centrally disposed metal rod arranged in each rail and having its ends projecting therefrom, one end of said rod terminating in a hook and the 65 other end of said rod terminating in an eye,

whereby the ends of the adjoining rails occupying the communicating recesses are locked together through the interengagement of the hook and eye of said rails, the recess on one side of each upright being of greater 70 height than the recess on the other side in order to permit upward displacement of the hook end of the rail preparatory to the seating thereof within the corresponding eye portion.

75 In testimony whereof I hereunto affix my signature this 17th day of February, 1890.

ALLEN B. DOWELL.
